Primary Examiner — John R Yeh(74) *Attorney, Agent, or Firm* — Fulwider Patton LLP(57) **CLAIM**

I, claim the ornamental design for a onion holding grill cleaner, as shown and described.

DESCRIPTION

FIG. 1 is a top perspective view of my new design for an onion holding grill cleaner;

FIG. 2 is a bottom perspective view thereof;

FIG. 3 is a top view thereof;

FIG. 4 is a right side view thereof;

FIG. 5 is a bottom view thereof;

FIG. 6 is a left side view thereof;

FIG. 7 is a front view thereof; and,

FIG. 8 is a rear view thereof.

The broken lines represent portions of the grill cleaner which form no part of the claimed design.
